AIR CYLINDER FOR INDEXING RATCHET
STOPS AND THE LIKE

Arthur M. Loungway, Oneida, N. Y.

Application February 5, 1947, Serial No. 726,632

2 Claims. (Cl. 121—38)

1

This invention relates to an air cylinder such as is employed for indexing ratchet stops or the like on machines such as grinders, indexing machines, punch presses and the like.

A primary object of the invention is to accelerate the speed of action of air cylinders of the type to which this invention relates.

Another object is to regulate the length of stroke of the piston rod of an air cylinder without requiring that the air cylinder or machine on which it is employed be in any way altered or dismantled.

A further object is to eject work from punch presses or the like with accuracy and rapidity.

The above and other objects may be attained by employing this invention which embodies among its features a body block having an axial bore extending into one end, said block having a pair of transversely extending bores therethrough which lie along spaced parallel axes lying in a plane perpendicular to the axial bore near the inner end thereof, said block also having a relatively short port establishing communication between each transverse bore and the axial bore, one of said transverse bores being vented to atmosphere, a piston in the cylinder, a piston rod carried by the piston and extending outwardly through the axial bore, a normally open air pressure exhaust valve in the vented transverse bore and a normally closed air pressure inlet valve in the other transverse bore.

Other features include means automatically to close the exhaust valve in advance of the opening of the pressure inlet valve, an electromagnet for actuating the valve actuating means, and a needle valve to regulate the flow of pressure fluid through the port which communicates with the axial bore and the transverse bore containing the inlet valve.

Other features include adjustable means to regulate the length of the advanced stroke of the piston, and means to return the piston to initial position when the exhaust valve is opened.

In the drawings,

Figure 1 is a side view of an air cylinder and control mechanism embodying the features of this invention,

Figure 2 is a top plan view of the cylinder illustrated in Figure 1, certain portions being broken away more clearly to illustrate certain details of construction,

Figure 3 is a front end view of the air cylinder illustrated in Figures 1 and 2,

Figure 4 is a transverse sectional view taken substantially along the line 4—4 of Figure 1,

2

Figure 5 is a longitudinal sectional view taken substantially along the line 5—5 of Figure 2,

Figure 6 is a fragmentary transverse sectional view taken substantially along the line 6—6 of Figure 1, and

Figure 7 is a perspective view of the valve actuating lever.

Referring to the drawings in detail this improved air cylinder designated generally 10 comprises a body block 11 formed with an axial bore 12 equipped with a cylinder liner 13 as will be readily understood upon reference to Figures 5 and 6. As shown the axial bore 12 extends inwardly into the body block 11 from one end thereof and terminates short of the opposite end of said body block. Extending transversely through the body block 11 are spaced parallel openings 14 and 15 which lie along spaced parallel axes which extend in a plane lying perpendicular to the longitudinal axis of the bore 12. Formed in the block 10 and establishing communication between the bore 12 and each bore 14 and 15 are ports 17 and 18 by which communication is established between the axial bore 12 and the transverse bores. Extending through the side wall of the body block 11 and opening into the transverse bore 14 is a vent 19 for a purpose to be more fully hereinafter described. Extending upwardly from the body block 11 near the end entered by the bore 12 is a bracket 20 the upper end of which is pierced to receive a pivot pin 21 the purpose of which will more fully hereinafter appear. Formed on the end of the body block 11 opposite that entered by the bore 12 is a rectangular frame 22 in which a solenoid 23 is supported. This solenoid is connected to insulated conductors 24 and any suitable circuit closing device (not shown) with a source of electric power so that when the circuit is closed the solenoid will be energized to move the armature 25 thereof into the core. The upper or outer end of the armature 25 is equipped with spaced parallel ears 26 and a cross pin 27 extends transversely between the ears 26 and in spaced relation to the upper end of the armature.

Pivotedly supported on the pivot pin 21 is a lever arm 28 the end of which opposite the pivoted end projects through an enlarged opening in one end wall of the frame 22 and lies between the pin 27 and the upper end of the armature 25 so that when the armature is depressed through the energization thereof the lever arm 28 will be moved about its pivot 21. A compression coil spring 29 extends between the lever arm and the exterior of the cylinder body block 11 yieldingly to urge the lever arm 28 upwardly and against the action

of the solenoid. Extending laterally from the lever arm 28 at a point substantially midway between opposite ends thereof is a finger 30 which when the lever arm is lowered is adapted to engage and open the pressure inlet valve to be more fully hereinafter described. Pivotaly supported as at 31 on the frame 22 above the lever arm 28 is a rock arm 32, one end of which is adapted to be engaged by the finger 30 when the lever is held upwardly under the influence of the spring 29. The end of the rock arm 32 opposite that which contacts the finger 30 intersects the longitudinal axis of the bore 14 and is adapted to be engaged by the valve stem of the exhaust valve to be more fully hereinafter described.

Mounted for longitudinal sliding movement within the piston liner 13 is a piston 33 carrying a piston rod 34. This rod 34 extends axially from the piston 33 outwardly through a cylinder head 35 and an externally screw threaded tubular boss 36 carried thereby which extends outwardly therefrom in axial alignment with the piston rod. Formed in the cylinder head 35 in spaced concentric relation about the boss 36 is an annular row of radially spaced openings 37 through which stop rods 38 enter the bore 12. The outer ends of these stop rods are fixed in a follower ring 39 which rides longitudinally of the boss 36 and is adapted to abut an adjusting nut 40 threaded on the boss. The inner ends of the stop rods 38 are adapted to contact the piston 33 as the latter moves outwardly under the influence of fluid under pressure admitted to the bore 12, so as to limit the stroke of the piston and piston rod to suit varying conditions. When the nut is advanced to a point nearest the head 35, the inner ends of the stop rods 38 will hold the piston 33 against any longitudinal movement, but when the nut 40 is retracted to its fullest extent with relation to the head 35 the full stroke of the piston will be obtained. A compression coil spring 41 encircles the piston rod 34 between the piston 33 and the head 35, yieldingly to urge the piston toward the innermost end of the bore 12 as will be readily understood upon reference to Figure 5.

Entering the bore 15 is a valve cage 42 carrying at its upper end a conventional packing gland 43 to form an air tight junction about a push rod 44. The upper end of the push rod is located directly beneath the finger 30 while the lower end of the push rod seats on a valve stem 45 mounted for longitudinal movement through a bore 46 which extends longitudinally through the cage 42 and communicates at its upper end with the recess in which the packing gland is fitted and at its lower end with an enlarged bore 47 entering the valve cage 42 from the end opposite the packing gland. A valve seat 48 is formed at the junction of the bores 46 and 47 and carried on the end of the valve stem 45 which enters the bore 47 is a valve 49 which is adapted to cooperate with the seat 48 in arresting the flow of fluid through the cage. A compression coil spring 50 bears at one end on the valve 49 while its opposite end is supported on a spring ring 51 which seats in an annular groove formed in the cage 42 intermediate the upper and lower ends of the bore 47. The end of the bore 47 opposite that terminating in the valve seat 48 is internally screw threaded for the reception of a coupling nipple 52 by means of which the device may be coupled to a suitable source of air pressure supply (not shown). Formed in the periphery of the cage 42 near the valve seat 48 is an annular groove 53 and radial passages 54 establish communication between

the annular groove 53 and the axial bore 46 so that when the valve 49 is opened fluid will flow through the pipe or nipple 52, the bore 47 and bore 46 thence outwardly through the passages 54 and 5 the passage formed by the annular groove 53 and port 13 into the bore 12 behind the piston 33. Fitted in the bore 14 is the cage 56 of the exhaust valve which comprises a cylindrical body having a bore 57 entering one end which communicates 10 at its inner end with an enlarged longitudinally extending axial bore 58 the opposite end of which communicates with a further enlarged axial bore 59 the lower end of which is internally threaded to receive a plug 60. The junction of 15 the bores 58 and 59 is tapered to form a valve seat 61 for a valve 62 carried at the lower end of a valve stem 63 which extends upwardly through the bores 58 and 57 and to a point immediately below the bottom edge of the rock arm 32 as will 20 be readily understood upon reference to Figure 4. Formed in the periphery of the cage 56 near opposite ends are annular grooves 64 and 65. Radial passages 66 and 67 are formed in the cage 56 to establish communication between the longitudinal bores 58 and 59 with the passages formed 25 by the walls of the grooves 64 and 65 and the wall of the transverse bore 14. The groove 65 is so located that communication is established between the interior of the bore 58 and atmosphere 30 through the vent 19. The groove 66 is so located as to establish communication with the interior of the axial bore 12 through the port 17 and it will thus be seen that when the valve 62 is lifted off of its seat 61 any air contained within the 35 axial bore 12 may be exhausted through the vent 19. A compression coil spring 68 rests on the plug 60 and bears against the end of the valve 62 opposite the stem so that the valve is normally urged into closed position and yieldingly so held by the 40 spring. When the valve is in closed position the stem 63 thereof is yieldingly projected into contact with the rock arm 32, and with the rock arm at rest as illustrated in Figures 3 and 4, the valve 62 is held in an open position as will be readily 45 understood upon reference to Figure 4.

A suitable attaching ear 69 projects outwardly from the frame 22 to serve as a mounting means by which the air cylinder may be attached to any suitable support on the machine for which it is 50 to be used.

In use the nipple 32 is coupled in any source of air pressure supply and the insulated conductors 24 are connected through a suitable switch means to a convenient power outlet with the air cylinder attached to the machine in 55 working position. Upon closing the circuit through the solenoid 23 it will be obvious that the armature 25 thereof will be moved against the spring 29, thus freeing the rock arm 32 to enable it to rock about its pivot 31. Pressure on the upper end of the valve stem 63 will thus be released and the stem 63 with the valve 62 will move upwardly under the influence of the 60 spring 68 until the valve 62 seats against the seat 61. Such upward movement of the valve stem 63 will cause the rock arm 32 to rock about the pivot 31 out of its straight horizontal position. Immediately following the seating of the valve 62 against the seat 61, the finger 30 contacts the push rod 44 and moves the valve 49 to open position thus admitting air to the cylinder and causing the piston 33 and piston rod 34 to be advanced against the pressure of the 65 spring 41. The distance which the piston 33 and piston rod 34 may be moved is regulated by ad-

justing the thumb nut 40 longitudinally on the stem or boss 36 so that the stop rods 38 may be pushed through their respective openings 37 until the follower 39 contacts the thumb nut 40. It is obvious that the magnitude of movement of the piston 33 and piston rod 34 may be varied even with the cylinder or axial bore 12 containing air under pressure so that the piston is in an advanced position. In this way the length of stroke may accurately be regulated to suit conditions under which the piece of equipment is to operate. By reason of the short distance between the opposite ends of the ports 17 and 18 it is obvious that the piston 33 may be reciprocated with extreme rapidity as there is no appreciable time lag between the opening of the valve 49 and the flow of the air into the bore 12. In order that the flow of fluid through the port 18 may be regulated I provide a needle valve 70 of conventional form which enters the block 11 radially thereof and may be moved to increase or decrease the obstruction of the port 18. Upon de-energizing the solenoid 23, the lever arm 28 will move upwardly under the influence of the spring 29 thus causing the finger 30 to engage the end of the rock arm 32 remote from the valve stem 63 so as to cause the rock arm 32 to rock about its pivot 31 and depress the valve stem 63 against the effort of the spring 68 and unseat the valve 62 from the seat 61 to permit air contained in cylinder 11 to escape to atmosphere through the vent 19.

While in the foregoing there has been shown and described the preferred embodiment of this invention it is to be understood that minor changes in the details of construction, combination and arrangement of parts may be resorted to without departing from the spirit and scope of the invention as claimed.

I claim:

1. An air cylinder for indexing ratchet stops or the like which includes a body block having an axial bore entering one end, said block having a pair of transverse bores extending therethrough which lie along spaced parallel axes lying in a plane perpendicular to the axial bore near the inner end thereof and a relatively short port establishing communication between each transverse bore and the axial bore, one of said transverse bores being vented to atmosphere, a piston in the cylinder, a piston rod carried by

the piston and extending outwardly through the axial bore, a normally open air pressure exhaust valve in the vented transverse bore and a normally closed air pressure inlet valve in the other transverse bore, a lever pivotally supported on the frame, means yieldably to hold said lever elevated, electromagnetic means for depressing the lever, a finger extending laterally from the lever intermediate its ends for opening the inlet valve when the lever is depressed and means actuated by the finger for holding the exhaust valve open when the lever is elevated.

2. An air cylinder for indexing ratchet stops or the like which includes a body block having an axial bore entering one end, said block having a pair of transverse bores extending therethrough which lie along spaced parallel axes lying in a plane perpendicular to the axial bore near the inner end thereof and a relatively short port establishing communication between each transverse bore and the axial bore, one of said transverse bores being vented to atmosphere, a piston in the cylinder, a piston rod carried by the piston and extending outwardly through the axial bore, a normally open air pressure exhaust valve in the vented transverse bore and a normally closed air pressure inlet valve in the other transverse bore, a lever pivotally supported on the frame, means yieldably to hold said lever elevated, a finger extending laterally from the lever intermediate its ends for opening the inlet valve when the lever is depressed and means actuated by the finger for holding the exhaust valve open when the lever is elevated.
